(57) **CLAIM**

The ornamental design for a camera, as shown and described.

DESCRIPTION

FIG. 1 is a front and right side perspective view of a camera showing my new design;

FIG. 2 is a back and left side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The broken lines depict portions of the camera that form no part of the claimed design.

The dash-dot broken lines denote the boundary of the claim and form no part of the claimed design.

1 Claim, 8 Drawing Sheets
